P. Cooper,

Cradle,

Patented Mar. 27, 1815.

Mr. Cooper
Sellers Patent

1870-71

March

2281X

The invention referred to in this Sellers Patent and Working part of the same containing a description in the words of the said Mr. Cooper himself, of his improvement in the Cradle.

The base or pieces are made of timber or plank of about ten feet and a half long & four inches broad & one inch & half thick which are made to support the whole machinery perpendicular in the centre of each of them. There is a part of about four feet and half high eight inches wide at bottom and three inches at the top & one inch thick which are connected together at the top and bottom of the bars. The bar is then fastened in his frame inside to inside of the frame and is six inches broad & one inch thick and is a round super structure of it which passes through the frame and appears open to the outside of the said frame the bar is one inch and half broad to the same length and thickness as the bar & may be fastened in a similar way. Another bar is placed vertically from resting on the lower bar and is fastened in the upper at about seven inches from one of the top posts first mentioned; between these two parts last spoken of a cradle is made similar to that in a cradle the arms of which rests on a made to turn in the said frame at about one foot from the top the bar being used to the inner post and the outer end of it furnished with a hook with a cable or fastened on it for the purpose of winding up the machine as hereafter directed between this intermediate post and the one at the other end of the frame is hung a carriage for the child vehicle, may be made a cradle, a chair, a cradle, a chair, a sofa, a boudoir, a boudoir and a cradle the bottom of this cradle is over the top of the lower of the frame is suspended by the said arms of one such frame a greater part of the frame is fastened at each end of it and reaching nearly to the top of the frame where they are made to hang in or upon the said posts by means of two small wires turned at right angles the one next to the cradle vehicle extending through the post and having a flat top of a clock working in the said

Crane wheel, a weight of sufficient gravity being suspended by a cord wound up upon the axis of the wheel and the weight being suspended in such a way to resemble the pendulum of a clock, so that the weight will run loose. In order to winding up the machinery of the hoist when it is only necessary to turn the crank of the wheel to loose up the weight with a catch so that before upon its going the pulley may be elevated and drawing agent from the wheel before winding up by means of a lever placed on the left of the machine and made to lift up the load of the cradle by a wire passing from the lever down through the upper cap has been secured the end of the pulley -

The principal advantage a patient right consists in giving such a cradle by means of straight beam, stone and pulley
